UNITED STATES PATENT OFFICE.

CLINTON MARVIN HOGGE, OF RICHMOND, VIRGINIA.

ASH-RECEPTACLE.

1,296,521.

Specification of Letters Patent.

Patented Mar. 4, 1919.

Application filed September 6, 1918. Serial No. 252,924.

To all whom it may concern:

Be it known that I, CLINTON M. HOGGE, a citizen of the United States, residing at Richmond, in the county of Henrico and State of Virginia, have invented certain new and useful Improvements in Ash-Receptacles; and I do hereby declare the following to be a full, clear, and exact description of the invention, such as will enable others skilled in the art to which it appertains to make and use the same.

This invention relates to receptacles, and more particularly to cigar ash trays or receivers.

It is one of the objects of the present invention to provide a simple, practical and inexpensive ash tray for cigar ashes, which device may be readily attached in an inconspicuous but convenient position to various forms of supports, such for instance as the edge of a flat top table, arm chair, or to a shelf, or to the edge or a ledge at one side of an article of furniture such as a desk having a top cabinet structure. It is one of the particular objects of the present invention to provide an ash receptacle having a funnel with means for clamping it to a desired or convenient support, and having also a detachable bowl which may be quickly connected to or detached from the funnel or hopper, and which bowl is supported in an inconspicuous or concealed position, and where it will form no obstruction at the surface of the table or other support to which the device may be attached.

With the above and other objects in view, the invention consists in the construction, the combination, and in details and arrangements of the parts as more particularly set forth in the following specification relative to the embodiment illustrated in the accompanying drawing, in which—

Figure 1 is a plan view showing the device as applied to a table;

Fig. 2 is a vertical, central section through the device;

Fig. 3 is a vertical section through a modified form of the device adaptable for attachment to the side of a cabinet structure having vertical side walls with a projecting edge or ledge portion;

Fig. 4 is a plan view of another modification of the device showing a simple means for providing for the temporary connection of the bowl to the hopper.

Fig. 5 is a plan view of Fig. 3.

In the form of the invention illustrated in Figs. 1 and 2, there is provided a hopper or funnel member 2 illustrated as approximating in plan a segmental outline, though obviously it may be of any other desired shape. The funnel has on one of its flat and vertical faces a lug 3 forming a member of a clamp comprising a movable friction plate 4 which is mounted on the end of a screw 5 having a thumb piece 6 at its lower end, the screw being threaded in a nut or threaded portion 7 attached to or formed upon a horizontal plate or connecting member 8 which is attached to the bottom of the hopper 2. The hopper is adapted to be clamped for instance to the edge of a table T by the adjustment of the clamp member 3 over the top of the table when the hopper is pushed against the edge of the same and then by tightening up the clamp screw 5 the hopper with the base or plate member 8 is rigidly though detachably secured to the table. The lower end of the hopper is designed to discharge into a suitably shaped bowl 10 which in Figs. 1 and 2 is provided with internal threads 11 at its top edge, the bowl in this instance being circular as is the plate 8 which latter has a threaded portion 9 complementary to the threads 11 of the bowl 10. The device therefore may be inexpensively constructed and forms a very convenient and ornate receiver for cigar ashes, and provides for the ready removal of the bowl 10 from the hopper 2 which is affixed to the edge of the table or other supporting shelf T. The hopper being of relatively small proportions does not form any obstacle occupying valuable space on the top of the table, which for instance may be an office desk where surface area is very necessary. It will be seen that the ashes from the cigars may be readily knocked into the hopper 2 and through this fall into and be held in the bowl or receiver 10 which eliminates the scattering of the ashes over the top of the table, and also avoids the accidental knocking over or upsetting of the ash tray as is commonly done in types of ash trays which rest immediately upon the top of the table. Also the ashes are prevented from being blown around by reason of being collected in the bowl 10 which is substantially covered by the plate 8.

It is also desirable to provide a form of detachable bowl and hopper which may be readily connected to the marginal or edge

portion of a shelf or table top such for instance as may be found in roll top or other desks having a cabinet structure C, (Fig. 3) above the top of the table T for which purpose I provide the hopper 2 with clamping means 3—4—5 to permit attachment of the hopper to the ledge at the side of the cabinet, but in such adaptations of the device, the bowl 10 can not extend underneath of the table as shown in Fig. 2 but must be arranged to hang beside the wall W. Therefore the bowl 10' (Fig. 3) is of such form that when connected to the table T it extends down beside the wall W. In the illustrated form of the device for attachment to the side of a cabinet desk, the bowl 10' is provided with a mouth portion 10^a adapted to be readily screwed or attached to the base end of the hopper 2 and be held thereby any suitable means, as for instance by screw threads allowing the ready attachment and detachment of the bowl 10' to the hopper 2.

A modified form of attaching means for connecting the bowl 10 to the hopper 2, (Figs. 1 and 2) is illustrated in Fig. 4 in which the plate 8 of the hopper 2 is provided at diametrically opposite points with downwardly and inturned clips or lugs 8' adapted to pass over and embrace the flange 30 or beaded edge 11^a of the hopper 10.

The funnel is provided at its upper portion with a rest 13 on which a cigar or cigarette may be laid so that its ashes will fall through the funnel into the hopper. It is also provided with a compartment 16 to hold matches.

What is claimed is:

1. An ash receptacle comprising a hopper with one side adapted for adjustment 40 against the edge of a shelf-like support and

having a lateral abutment lug to rest upon the support; a base plate on the bottom of the hopper and through which it discharges, said plate extending laterally so as to project beneath the support to which the hopper 45 may be applied; means coöperative with the lug to clamp the hopper *in situ*; and a bowl detachably connectible to the plate to extend, with it, beneath the support.

2. An ash receptacle comprising a hopper with one side adapted for adjustment 50 against the edge of a shelf-like support and having a lateral abutment lug to rest upon the support; a base plate on the bottom of the hopper and through which it discharges, 55 said plate extending laterally so as to project beneath the support to which the hopper may be applied; means coöperative with the lug to clamp the hopper *in situ*; and a bowl detachably connectible to the plate to 60 extend, with it, beneath the support, said means including a thumb screw threaded in the plate and opposed to the lug.

3. An ash receptacle comprising a hopper with one side adapted for adjustment 65 against the edge of a shelf-like support and having a lateral abutment lug to rest upon the support; a base plate on the bottom of the hopper and through which it discharges, said plate extending laterally so as to project beneath the support to which the hopper may be applied; means coöperative with the lug to clamp the hopper *in situ*; and a bowl detachably connectible to the plate to extend, with it, beneath the support, the hopper 70 having at its top means to serve as a cigar rest.

In testimony whereof I affix my signature.

CLINTON MARVIN HOGGE.
